UNITED STATES PATENT OFFICE

166,017

BOTTLE

Ella M. Barq, Biloxi, Miss., assignor to Barq's
Inc., Biloxi, Miss., a corporation of Mississippi

Application April 5, 1950, Serial No. 8,979

Term of patent 14 years

(Cl. D58—8)

To all whom it may concern:

Be it known that I, Ella M. Barq, a citizen of the United States, residing at Biloxi, county of Harrison, State of Mississippi, have invented a new, original, and ornamental Design for a Bottle, of which the following is a specification, reference being had to the accompanying drawing, forming a part thereof, and wherein

I claim:

The ornamental design for a bottle, substantially as shown.

ELLA M. BARQ.
